COKE OVEN LEVELER BAR SEALING DEVICE

James McIntosh, Pittsburgh, Pa.

Application March 22, 1940, Serial No. 325,424

6 Claims. (Cl. 214—23)

This invention relates to coke ovens, and particularly to improved means for sealing the opening through which the conventional leveler bar of a pusher machine operates.

It is well known to those skilled in the art that modern by-product coke ovens are built in batteries and that the coke is adapted to be periodically discharged from the ovens by a known type of pusher machine traveling along a track located on the side of the oven opposite that from which the coke is discharged. The pusher machine is generally equipped with a power-operated pusher ram, and the respective charges of coke are pushed from the various ovens by the pusher, according to a predetermined schedule.

Conventional pusher machines are also equipped with mechanism for removing the oven door and replacing it after each charge of coke has been pushed. It is also conventional to provide pusher machines with a leveler bar comprising an elongated member which is reciprocated through a small door opening near the top of the oven so as to cause the peaks of coal in the oven to be leveled off to a substantially uniform depth.

Heretofore, the operation of leveling was accompanied by a great loss of gas and other products of combustion which at the leveling stage of operation of the oven are particularly dense. Frequently these gaseous products become ignited, resulting in a burst of flame which is not only confusing to the pusher operator, especially at night, but otherwise detrimental to efficient operation. Moreover, heretofore air objectionably entered the coking chamber through the unsealed leveler door opening, thus increasing the amount of suction required to remove the gas from the oven chamber and having other detrimental effects.

It is an object of the present invention to provide sealing means which, during the operation of the leveler bar, will be effective in coaction therewith to substantially prevent the escape of gaseous products from the coking chamber or the entry of air into the chamber.

It is a further object of the invention to so coordinate with the leveler bar of a coke oven pusher machine the various instrumentalities herein shown, described and claimed, that they singly and jointly perform the functions set forth.

For a complete understanding of the invention, reference should be made to the accompanying drawings, the following detailed description, and the appended claims.

In the drawings, Figure 1 is a transverse section through a portion of the pusher side of a coke oven showing as much of a conventional type of pusher machine as is necessary for a complete understanding of the present invention.

Figure 2 is an enlarged view of the parts shown in Figure 1, showing in greater detail the sealing device of the present invention and related operating mechanism.

10 Figure 3 is a detailed section on line III—III of Figure 2.

Figure 4 is a horizontal section on line IV—IV of Figure 2.

15 Figure 5 is a transverse section on line V—V of Figure 2.

Referring more particularly to the drawings, 10 represents a conventional type of coke oven, with coking chamber 12 adapted to be closed by an end door 14 held in the usual manner and adapted to be engaged and disengaged by a suitable door-operating mechanism carried by the pusher machine 16. The pusher machine, which travels in front of the battery of ovens on suitable track rails 18, will carry the usual ram or pusher, not shown, for discharging coke from the chamber 12. Inasmuch as the door-operating means and the pusher mechanism per se form no part of the present invention, they will not be further shown or described.

20 30 In the normal operation of coke ovens, the coal to be coked is discharged from an overhead traveling hopper car through suitable openings in the roof. The conventional discharging practice results in the formation of peaks of coal

35 which it is desirable to level off. To accomplish such leveling, the pusher machine is equipped with a leveler bar 20 mounted for reciprocating movement between a plurality of upper flanged guide rollers 22—22 and lower flanged guide rollers 24—24, journaled in suitable brackets 26 and 40 28 which are carried by the framework of the pusher machine.

The leveler bar is reciprocated by means of a cable 30 wrapped several times around a drum 32. One portion of the cable 30 extends forwardly and around a guide sheave 34, and is attached at 45 36 to the leveler bar. Another portion 38 of the cable extends rearwardly of the drum and around a rear guide sheave 40, and is attached at 50 42 to the leveler bar. As thus arranged, it will be apparent that when the leveler bar motor 44 is energized, motion will be transmitted through reduction gearing 46 to the drum 32 to thus impart a stroke to the leveler bar of desired length 55 to properly level off the peaks of coal in the oven.

The motor 44 is of the reversible type and is controlled by conventional means forming no part of the invention.

In accordance with this invention, a sealing device, indicated generally at 48, is provided, which is slidably associated with the leveler bar and is effective to prevent the escape of gas from the coke oven chamber or prohibit the entrance of air thereinto.

Conventional coke ovens are usually provided with a leveler bar opening 50 which is formed in a frame 52. The opening 50 is normally closed by a leveler opening door (not shown). Heretofore, during the leveling operation, at which time the door referred to must of necessity be open, gas could escape from the oven, and during certain stages, air could also be drawn into the oven. To prevent such undesirable occurrences, I provide a sealing device which in the embodiment illustrated comprises a sleeve which is independently mounted for sliding movement relative to the leveler bar and arranged to embrace the same and close the door opening. This sleeve, in combination with certain transverse partitions incorporated in the improved leveler bar structure, effectively prevents escape of gas from the oven during the operation of leveling the coal by reciprocating movement of the leveler bar. To this end I preferably construct the leveler bar of a pair of parallel bar members 54-54 with transverse partition-like spacers between them. At its forward end the leveler bar is equipped with a poker head 58 which in the embodiment illustrated is of pointed form.

The length of the sealing sleeve 48 is greater than the longitudinally measured distance between any two adjacent spacers 56. Thus at all times at least one spacer will serve as a partition to prevent the escape of gas through the sleeve. From the drawings it is clear that at points other than those embraced by the sleeve, the space between the bars 54-54 is open at top and bottom.

The sealing sleeve is slidably supported with freedom of independent movement relative to the leveler bar by means of longitudinally-extending rods 60-60 whose forward ends are bolted to brackets 62 secured to the opposite side walls of the sleeve 48. The rods 60 ride between upper and lower grooved rollers 64 and 66 which are carried by suitable journal pins secured to channel members 68 constituting part of the framework of the pusher machine.

Each rod 60 is connected by means of a link 70 to a lever 72 carried by rock shaft 74 which also has secured thereto an arm 76 from the free end of which is suspended a weight 78. This weight, through the connections described, serves to yieldably urge the sealing sleeve 48 toward the face of the leveler bar door-opening frame 52, and is effective to hold the forward flanges 80 of the sealing sleeve firmly in engagement with the marginal portion of the frame surrounding the leveler bar door opening.

A crosshead 82 is slidably mounted on supporting rods 84 secured to any suitable portion of the pusher machine frame, and is connected by means of a cable 86 with a pin 88 carried by the arm 72. This crosshead carries a detent 90 for coaction with a lug 92 projecting laterally from the leveler bar. As thus arranged, it will be apparent that when the motor 44 is energized it will cause the leveler bar to advance through the door opening, and the weight 78, acting through arms 76 and 72, will cause the sealing sleeve 48 to move forward with the leveler bar from the

full line position of Figure 1 to the dotted line position in which the forward flange 80 of the sealing sleeve contacts the front face of the leveler bar door-opening frame. The weight 78 thereafter yieldingly holds the sealing sleeve in contact with the door frame, while the leveler bar continues its forward movement. The bar may be operated to give various intermittent forward and rearward strokes. During such operation, one or more of the spacers 56 carried by the leveler bar will function as transverse partitions or barriers to prevent escape of gas through the sleeve or the entry of air into the oven through the sleeve.

After the leveling operation is completed, the leveler bar will be retracted, to the position shown in Figure 1, for example, and during such movement the lug 92 will engage the detent 90 and thus rock the arm 72 to retract the sealing sleeve 48, whereupon the usual leveler bar door will be closed.

Manually operable braking means of the type shown in Figure 2 are preferably provided to releasably hold the sealing sleeve in a closed position. These means include brake drum 94 with which cooperates a band brake 96, one end of which is connected at 98 to a lever 100 which is pivoted at 102 to a suitable fixed bracket. Also carried by the pivot is a crank arm 104 which in turn is pivotally connected to one end of the brake band. A spring 106 is secured at one end to the lever 100 and at its opposite end to a fixed anchorage 108. Thus the spring normally tends to rock the brake lever 100 to release position. For applying the brake there is a pedal 110 which rocks a bell crank 112 carried by rock shaft 114 in a direction to apply tension to the brake cable 116 passing around a guide sheave 118 and attached at 120 to the brake lever 100. As thus arranged, the operator can manually restrain the forward movement of the seal sleeve whenever deemed advisable, and also, by locking the brake, the sleeve can be held in firm engagement against the leveler door frame during the leveling operation.

As illustrated in detail in Figure 3, the leveler bar sealing sleeve 48 comprises two main elements, one consisting of a generally U-shaped portion, as viewed in cross section, including the opposite side walls 122 and 124, joined by top wall 126. Following the general U-shaped contour of these parts is the forward marginal flange 80 which overlaps, and is arranged to be firmly seated against, the edge of the shell-like flange 128 which surrounds the lever bar opening in the door frame of the oven, indicated generally at 52.

The top member 126 of the leveler seal sleeve slides freely on the top edges of the members 54-54 of the leveler bar. The bottom of the sealing sleeve in the embodiment of the invention illustrated includes a plate 130 which is pressed upwardly against the under side of the leveler bar by springs 132 which surround guide studs 134 carried in cross rods 136. The bottom plate 130 has secured thereto a cross rod 138 which extends through guide slots 140 so as to restrain the bottom plate against endwise movement and yet permit the same to be yieldingly pressed by the springs 132 against the under side of the leveler bar.

The intake of air during charging has a material effect on the suction induced by a steam jet in the standpipe during charging. Any reduction in this air intake should result in the use of less steam and consequently less condensates

in the gas to be later processed and disposed of.

Less air into the gas will result in decreased gas dilution and should also result in a reduction in the nitrous oxide compounds in the gas.

Less air into the gas during charging will result in more uniform pressure regulation with lower peaks and a lower average suction.

The use of this sealing device will eliminate the glare from the leveler operator's eyes during charging.

While I have described quite precisely the specific embodiment of the invention herein illustrated, it is to be understood that the drawings and description are to be interpreted by way of example rather than limitation, since various modifications and substitutions of equivalents may be made by those skilled in the art without departure from the invention as defined in the appended claims.

I claim:

1. The combination with a coke oven having a leveler opening in one end thereof, of a pusher machine having a leveler bar, mechanism for reciprocating the same into and out of the oven through said leveler opening, a sealing member embracing the leveler bar and having a flanged portion for sealing engagement with the marginal face of the oven adjacent said opening, means for supporting said member with freedom for independent slidable movement with relation to the leveler bar, yieldable means tending to press said member into sealing engagement against the face of the oven, and means movable in unison with the leveler bar for overcoming the effect of said yieldable means upon a predetermined outward movement of said leveler bar.

2. The combination with a coke oven having a leveler opening on one end thereof, of a pusher machine having a leveler bar, mechanism for reciprocating the same into and out of the oven through said leveler opening, a sealing member embracing the leveler bar, means for supporting said member with freedom for independent slidable movement in relation to said leveler bar, yieldable means tending to press said member into sealing engagement with the face of the oven adjacent said pusher opening, and means on the leveler bar for imparting withdrawing movement to said member upon rearward movement of the leveler bar..

3. The combination with a coke oven having a leveler opening in one end thereof, of a pusher machine having a leveler bar, mechanism for reciprocating the same into and out of the oven through said leveler opening, a sealing member embracing the leveler bar and having a flanged portion for sealing engagement with the face of the oven adjacent said opening, means for supporting said member with freedom for indepen-

dent slidable movement with relation to the leveler bar, a pivoted lever having a connection with said sleeve, means tending to move said lever in a direction to urge the sleeve toward the oven, a manually controlled brake for preventing movement of said lever, and means actuated upon an outward movement of the leveler bar for rocking said lever in a direction opposite to that before-mentioned.

4. The combination with a coke oven having a leveler opening in one end thereof, of a pusher machine having a leveler bar, mechanism for reciprocating the same into and out of the oven through said leveler opening, a sealing member embracing the leveler bar and having a flanged portion for sealing engagement with the marginal face of the oven adjacent said opening, means for supporting said member with freedom for independent slidable movement with relation to the leveler bar, a pivoted lever having a connection with said sleeve, a weight tending to rock said lever in a direction to urge the sleeve toward the oven, supporting rods for said sleeve, anti-friction guides for said rods, yieldable means urging said rods toward the coke oven, a slidably mounted member having a connection with said lever and means on the leveler bar adapted to engage the last-named member so as to limit the forward movement of the sleeve relative to the leveler bar and to retract the sleeve after the leveler bar has moved outwardly a predetermined distance.

5. In horizontal coke ovens in which the charge in an oven is leveled by a leveler-bar operating through a leveler-door, means for closing substantially any gap between the leveler-bar and the leveler-door opening during the operation of leveling a charge, said means comprising a sealing plate fitting closely around at least the top and sides of the leveler-bar, which sealing plate is large enough to cover the leveler-door opening, guide members attached to the sealing plate to permit the sealing plate to ride on the leveler-bar, and means to hold the sealing plate against the leveler-door opening during the operation of leveling a charge.

6. In horizontal coke ovens in which the charge is leveled by a leveler-bar operating through a leveler-door, means for closing substantially any gap between the leveler-bar and the leveler-door opening during the operation of leveling a charge, said means comprising a sealing plate of area greater than the leveler-door opening and fitting closely around at least the top and sides of the leveler-bar, which sealing plate is held against and extends over the leveler-door opening during the leveling operation.

JAMES McINTOSH.
